COMBINED SHIPPING CONTAINER AND
EASEL FOR DISPLAY DEVICESRusling Wood, East Orange, N. J., assignor to
Rusling Wood, Inc., New York, N. Y., a corpora-
tion of New York

Application March 17, 1937, Serial No. 131,292

8 Claims. (Cl. 40—124.1)

This invention relates to display devices and particularly to a shipping container therefor, a removable part of which forms an easel or support for the display device.

Display devices of cardboard, pulp-board or similar stiff material are widely used to advertise and to display merchandise. Such devices are frequently of relatively large size and elaborately decorated with cut-out figures having projecting parts. Devices of this type require careful and relatively expensive packing for shipment to avoid damage. An easel or support for the device is usually attached to the back thereof, and the packing case is removed and discarded when the device is set up.

It is the object of the present invention to provide a combined shipping container and easel for display devices which affords protection during transportation and is transformed by simple manipulation into a sturdy support for the device when it is used for display purposes.

Another object of the invention is the provision of an exceptionally strong and rigid easel by folding a portion of the shipping container.

A further object is the provision of a rigid easel constructed of folded sheet material, with the folded sections interlocked.

Among the advantages of the invention is the provision of a more rigid support than otherwise would be available because the shipping container is of necessity made of substantial material, which provides the easel or support. Another advantage is a considerable saving in cost due to the elimination of the easel as commonly provided.

Other objects and advantages of the invention will be understood by reference to the following specification and accompanying drawing, in which

Fig. 1 is a view in perspective of the front of a characteristic display device;

Fig. 2 is a similar view of the back of the device showing the easel assembled for use;

Fig. 3 is a section on the line 3—3 of Fig. 2;

Fig. 4 is a section on the line 4—4 of Fig. 3;

Fig. 5 is a view in perspective of the shipping container in the form in which it is shipped and illustrating the manner in which it is opened;

Fig. 6 is a section on the line 6—6 of Fig. 5;

Fig. 7 is a section on the line 7—7 of Fig. 5;

Fig. 8 is a view similar to Fig. 5, illustrating the further procedure in opening the shipping container;

Fig. 9 is a view in perspective illustrating the procedure in setting up the easel; and

Fig. 10 is a view similar to Fig. 9 illustrating the completion of the setting up operation.

Referring to the drawing, 5 indicates a display device which may be made of any suitable stiff sheet material such as cardboard, pulp-board, and the like. It may carry any desired advertising material applied preferably by lithography, although the device may be decorated in any suitable manner. It will be understood that the particular form of the display device, including the cut-out figure, forms no part of the present invention and may be modified to meet the particular advertising purpose.

The display device is enclosed within a shipping container consisting of a flat rear wall 6 with folded flaps 7 and 8 preferably overlapping to protect the enclosed device. The shipping container may be made of any suitable stiff sheet material, but corrugated board is preferred because of its strength and resistance to wear and tear of shipping. Instead of using integral flaps 7 and 8, the front of the container may, of course, consist of a single sheet secured in any suitable manner to the rear wall 6. The container is closed preferably at the ends by strips of adhesive tape 9 and 10, the latter being adapted to be slit with a knife or other sharp instrument in opening the container as indicated in Fig. 5.

The rear wall 6 of the shipping container is scored or perforated along lines 11, 12, 13, 14, 15, 16, and 17, as indicated in Fig. 5, to permit separation of the central portion of the rear wall from the marginal sections 18 and 19, and also to permit the folding of the central portion on the lines 13, 14, 16, 17, and 20, as indicated more clearly in Figs. 9 and 10. Thus, as indicated in Fig. 8, the marginal sections 18 and 19 are broken away from the central portion of the rear wall, and the lateral wings 21 and 22 having projections 23 and 24 thereon are folded to a position normal to the plane of the rear wall. The transverse brace 25 is then folded upwardly until it engages notches 26 in the lateral wings 21 and 22. The top brace 27 is then folded into engagement with the upper ends of the lateral wings 21 and 22, and the apron 28 is folded downwardly and slots 29 therein formed by perforated knockouts in the apron are engaged with the projections 23 and 24, the device being thus assembled as indicated particularly in Fig. 10.

The display device is preferably permanently connected to the rear wall 6 of the shipping container, but a separable connection may be provided, if desired. When the device has been assembled, as shown in Fig. 10, it may be set up.

The easel or support formed by the folded rear wall of the shipping container is rigid and substantial and will hold the display device securely in the desired position.

5 A substantial portion of the shipping container is thus utilized as an easel or support for the display device. The remaining portion of the shipping container may be discarded. A substantial saving is effected in thus providing an easel or support consisting of a part of the shipping container, whereas in the practice heretofore followed it has been customary to provide some form of support for the device attached to the back thereof and entirely separate from the shipping 10 container. The material of the shipping container is particularly adapted for use in forming the easel or support because the material employed is stiff and rigid. Furthermore, the improved form of support as illustrated and described herein is staunch and ensures that the display device will be held securely in its intended 15 display position.

20 Various changes may be made in the form, arrangement and construction of the parts without departing from the invention or sacrificing the advantages thereof.

I claim:

1. In a device of the character described, a 25 shipping container of stiff sheet material having a flat rear wall, a display device supported on the inner face thereof, the rear wall being scored to facilitate the removal of marginal sections and the bending of other sections for interlocking engagement to provide an easel for the display 30 device.

2. In a device of the character described, a 35 shipping container of stiff sheet material having a flat rear wall, a display device supported on the inner face thereof, the rear wall being scored to facilitate the removal of marginal sections and the bending of lateral and transverse sections for 40 interlocking engagement to provide an easel for the display device.

3. In a device of the character described, a

shipping container of stiff sheet material having a flat rear wall, a display device supported on the inner face thereof, the rear wall being scored to facilitate the removal of marginal sections and knock-out sections and the bending of other sections for interlocking engagement to provide an easel for the display device. 5

4. In a device of the character described, a 10 shipping container of stiff sheet material having a flat rear wall, a display device supported on the inner face thereof, the rear wall being scored to facilitate the removal of marginal sections and knock-out sections and the bending of lateral and transverse sections for interlocking engagement to provide an easel for the display device. 15

5. In a device of the character described, a 20 shipping container of stiff sheet material having a flat rear wall and overlapping wings forming the front wall, a display device supported on the inner face of the rear wall, the latter wall being scored to facilitate the removal of marginal sections and the bending of other sections for interlocking engagement to provide an easel for the display device. 25

6. In a device of the character described, a 30 shipping container of stiff sheet material having a flat rear wall, the rear wall being scored to facilitate the removal of marginal sections and the bending of other sections for interlocking engagement to provide a rigid easel. 35

7. In a device of the character described, a 40 shipping container of stiff sheet material having a flat rear wall, the rear wall being scored to facilitate the removal of marginal sections and the bending of lateral and transverse sections for interlocking engagement to provide a rigid easel. 45

8. In a device of the character described, a 45 shipping container of stiff sheet material having a flat rear wall and overlapping wings forming the front wall, the rear wall being scored to 50 facilitate the removal of marginal sections and the bending of other sections for interlocking engagement to provide a rigid easel.

RUSLING WOOD.
